CLAIM

The ornamental design for a combined signal flag, windsock and flagpole, as shown and described.

DESCRIPTION

FIG. 1 is a perspective view of a combined signal flag, windsock and flagpole showing my new design, the flagpole being truncated for ease of illustration;

FIG. 2 is a perspective view of a second embodiment of FIG. 1, the windsocks being substituted for the flags; and,

FIG. 3 is a perspective view of a third embodiment of FIG. 1, the flag and windsocks shown in combination.
